UNITED STATES PATENT OFFICE.

ROBERT C. HINDLEY, OF RACINE, WISCONSIN.

SKATE.

SPECIFICATION forming part of Letters Patent No. 286,199, dated October 9, 1883.
Application filed February 28, 1883. (No model.)

To all whom it may concern:

Be it known that I, ROBERT C. HINDLEY, of Racine, in the county of Racine and State of Wisconsin, have invented certain Improvements in Skates, of which the following is a specification.

My invention relates to the manufacture of skates; and it consists in a novel manner of constructing the same of sheet or plate metal, and in clamping or attaching devices applied thereto, as hereinafter more fully pointed out and explained.

In the annexed drawings, Figure 1 represents a perspective view of the complete skate; Fig. 2, a face view of one of the blanks of which it is mainly composed; Figs. 3 and 4, views illustrating two slightly-differing modes of attaching or uniting the blanks; Fig. 5, a cross-section of Fig. 1; Fig. 6, a perspective view of the fastening or clamping devices removed from the skate; Fig. 7, a detail view, illustrating a feature of construction of the clamping mechanism. Fig. 8 illustrates a modification.

The purpose of my invention is to produce a cheap and durable skate which shall be self-sharpening, light, and neat in appearance, and to provide the same with a ready and efficient means of attachment to the boot or shoe of a skater. With this object in view I construct the skate of sheet-steel or other suitable metal, in the manner presently described, and provide the same with a clamping device, which also may be stamped, punched, or cut from sheet metal. I desire, however, to state that I am aware of a previous attempt to construct skates of sheet metal, and therefore do not claim to be the originator of that idea, broadly considered, though I do believe myself to be the inventor of various important features and improvements not heretofore proposed or suggested.

Referring now to the drawings, the general appearance of the skate will be seen in Fig. 1, and in Fig. 2 is represented one of the two blanks of which the sole and runner are formed, each blank forming one-half of the sole and one-half of the runner.

The blank A consists of two parts, *a* and *b*, the first formed with ears *c* on the inner side, and with a spur or ear, *d*, on the outer side,

near the rear end, and the second made of the desired form of the runner, and joined to the first by cross-strips *e*, the whole being punched, stamped, or cut in one piece from a sheet or plate of metal, preferably and ordinarily steel. The two parts of the blank A are bent to stand at right angles one to the other, the bend being made at the inner side or edge of the sole part *a*, the ears *c* being, however, unbent, and allowed to project horizontally in the same plane with the sole part *a*. The ear *d* of each blank A is bent up at a right angle to the sole part *a*, and has its upper edge slightly bent over to form a lip or burr, *f*, to cause it to sink slightly into and firmly engage with the heel of the boot or shoe to which the skate is applied. The two blanks thus formed are united by lapping the ears *c* of one over those of the other and riveting the two together at each end of the skate, either by a single rivet, as in Figs. 1 and 4, or by two rivets, as in Fig. 3, in which latter case the ears require to be made longer than otherwise, in order to extend across the space *g*, between the blanks, and to lap over upon the sole part *a* at the opposite side. The space left between the edges of the two sole parts *a* is equal to or corresponds with the thickness or breadth of the runner, the two runner parts *b* extending vertically downward, parallel with each other, as shown in Fig. 5, and being separated and maintained in proper relation by an intermediate strip or filling, *B*, of wood, soft iron, or other metal, or other material capable of wearing away more readily than the thin steel bearing portions *b*. Wood will be found quite well adapted to the purpose, besides being cheap and easily applied; but any well-known substance suitable for the purpose may be used. The two side pieces, *b*, of the runner are firmly united by means of rivets *i*, or by screws, bolts, or equivalent fastenings passing through said parts and through the intermediate filling, as shown in Figs. 1 and 5, thus giving the runner great stiffness and solidity. The form of the runner—that is to say, its curvature or style, as "rocker," "half-rocker," &c.—may be varied to suit the trade, a simple straight runner being represented in the drawings, that being a common form.

For the purpose of readily attaching the skate to a boot or shoe, I provide the mechanism shown in Figs. 1 and 6, the ears *d* of the sole-plates acting in conjunction with the other parts, and constituting, preferably, a part of the fastening mechanism, though not absolutely essential thereto.

- C* represents a slide having an upturned portion, *j*, the upper edge of which is formed 10 with a lip or burr, *k*, serrated, if desired, and adapted to press against and embed itself into the inner front face of the boot or shoe heel, the slide being further provided with depending lips *l*, which are turned outwardly beneath 15 the sole-plate *a*, and serve to retain the slide in place. The slide may be applied to the 20 skate before the two blanks *A* are united; or it may be subsequently applied and the lips *l* turned outward after the slide is inserted in 25 place, with the depending lips extending downward through the open space *g*. The slide *C* is jointed to a lever, *D*, formed with a 30 lateral extension or finger-piece, *m*, and this lever is in turn jointed to a second lever or bar, 35 *E*, to the forward end of which are jointed two sliding clamps, *F*, extending backward from the point of connection at an angle to the slot or opening *g*, the body of each slide being slotted to receive a guiding and supporting 40 stud, *n*, formed with a T-head, and secured to the under side of the sole-plate *a*, the T form of stud being preferred, because it permits the application of the slides after the studs are secured permanently in place, it being 45 merely necessary to turn the slides to a position in which the slots *o* of the slides coincide with the length of the T-heads, care being taken to so set the studs that their heads shall extend across the slots when the slides 50 are in working position. Under this arrangement it will be seen the parts *D* *E* constitute a toggle-lever, the straightening of which forces the outer ends apart, and the bending or folding of which draws said ends together, 55 or toward each other. The slide *C* causes the end of lever *E*, attached to it, to move in line with the slot or opening *g*, and a washer, *p*, or equivalent projecting body, similarly guides the forward end of bar *E*.
- 50 The pivot *q*, which connects the levers *D* and *E*, is set slightly out of line with the pivots or joints *r* *s*, and a stop or shoulder, *t*, is formed on lever *D* to limit the movement of the levers inward beyond a straight line with each other. 55 Under this arrangement the levers will lock and be retained firmly in position when brought into line, because of the pivot *q* passing a line running through the centers of pivots or joints *r* *s*, as will be readily understood.
- 60 The skate being thus constructed, the levers *D* *E* are drawn out of line by taking hold of the finger-piece *m* and pulling it laterally with reference to the body of the skate; and this operation causes slide *C* to move forward and 65 slides *F* to move both backward and outward, affording room for the easy entrance of the

sole and heel of the boot or shoe between the clamps *F* and slide *C* and ears *d*. When the sole and heel are thus entered, the levers *D* *E* are pressed inward into line, and the slide *C* thereby forced backward and caused to engage with and embed itself in the face of the heel, while the ears *d* similarly engage with and embed themselves in the rear outer face, the clamping-slides *F* being at the same time forced forward and caused to clamp the sole of the boot or shoe, and the parts being all held in position by the locking of levers *D* *E* past the center, as explained.

In order to adapt the skates to shoes or boots of varying sizes and shapes, one of the levers *D* *E*, preferably the latter, is furnished with a series of holes, or with an elongated slot at its outer end, so that the pivot bolt, pin, or stud may be set closer to or farther from the pivot or joint *q*, thereby shortening or lengthening the distance between pivots or joints *r* *s*, and correspondingly increasing or diminishing the openings or spaces between the sole and heel clamps. If the slot is employed, as seems preferable, because of the greater convenience and nicety of adjustment which it permits, it will be found advisable to employ a pivot of the construction shown in Fig. 7—that is to say, consisting of a nut, *u*, having a tubular body just enough longer than the joint thickness of slides *F* to permit them to turn freely between the head or enlargement of the nut and the lever *E*, and a screw, *v*, passing through said lever into the nut, and serving to draw and hold it up firmly against the under side of the lever. If the separate holes are used—a plan which renders the accidental shifting of the pivot impossible—the screw may be screwed directly into the lower 100 of the slides *F*, being in either case preferably inserted from above, because of the greater convenience of so doing, and because it cannot then work out while the skate is in use. It is obvious that the lengthening and shortening 105 can be effected by making either of the levers *D* *E* in two parts, threading the approximate ends, respectively, with right and left hand threads, and joining them by a nut correspondingly threaded; or a screw-stem swiv- 110 eled in one of the parts may be employed.

The skate thus constructed is simple, cheap, and durable, much lighter than those of ordinary construction, and, owing to the more rapid wearing away of the filling than of the 115 side plates of the runner, is self-sharpening, which feature is one of great importance, as will be readily seen.

It will be seen that instead of slotting the clamping-slides *F* they may be formed with 120 lips or ears *w*, to guide them and retain them in place, the sole of the skate being in such case-slotted, as in Fig. 8, and the lips or ears *w* carried upward through the slots and bent over upon the sole-plate at each side, as shown, 125 the lips being slightly bent or rounded to permit the slides or clamps *F* to turn or swing.

as required; or the clamps F may be pivoted to the sole-plate and slotted at their inner ends, so that the movements of levers D and E will serve to swing the clamps about their pivots.

Any usual form may be given to the runners, and the runner portion may be connected with the sole-plate at the front or rear end, or at both ends, or made separate therefrom at said points, as preferred.

I am aware that skates have before been constructed the runners of which were composed of two pieces of metal, with an interposed strip of stiffening material; and this I do not claim, broadly, for while the strip I employ serves incidentally to give increased strength and stiffness to the skate, this alone is not its only object, the design being to render the skate self-sharpening by reason of the strip wearing away faster than the plates of the runner in consequence of its being softer.

Having thus described my invention, what I claim is—

1. The herein-described blank for the manufacture of skates, consisting of sole part a, runner part b, ears c c and d, and connecting strips e, substantially as shown.

2. The herein-described skate, consisting of two sheet-metal blanks, each constituting one-half of the sole-plate and one side of the runner, and a spacing-strip of softer material interposed between the side plates of the runner, and the whole united, substantially as explained.

3. In a skate, a runner consisting of two

thin steel side plates and an intermediate filling of softer material, adapted to wear away more rapidly than the steel, and thereby to render the skate self-sharpening.

4. In combination with a skate-body, a clamping or fastening mechanism consisting of slide C, levers D E, and sliding clamps F, all constructed and arranged to operate substantially as set forth.

5. In combination with the skate having ears d, the clamping mechanism consisting of slide C, levers D E, and sliding clamps F, arranged and operating as explained.

6. In combination with a skate having a metal sole-plate, and with a clamping mechanism such as described, a slide, C, provided with a clamping-face, j, and depending lips l, to pass beneath the sole-plate.

7. In combination with a skate, a clamping mechanism consisting of slide C, levers D E, and sliding clamps F, the pivot joining said levers being thrown out of line with those connecting the levers with the slides, and one of the levers being adjustably connected to its slide or slides, substantially as shown and described.

8. In a skate, a runner consisting of thin steel side plates, b, intermediate wooden strip, B, and rivets or fastenings i, passing through said parts and binding them together, as set forth.

ROBERT C. HINDLEY.
